UNITED STATES PATENT OFFICE.

JAMES H. ALEXANDER, OF PHILADELPHIA, PENNSYLVANIA, ASSIGNOR TO
THOMAS DEVLIN, OF SAME PLACE.

DESIGN FOR A STEAM-PIPE BRACKET.

SPECIFICATION forming part of Design No. 19,588, dated January 21, 1890.

Application filed November 15, 1889. Serial No. 330,483. Term of patent 14 years.

To all whom it may concern:

Be it known that I, JAMES H. ALEXANDER, a citizen of the United States, residing in the city of Philadelphia, State of Pennsylvania, 5 have invented a certain new and original Design for Steam-Pipe Brackets, of which the following is a full, clear, and exact description, reference being had to the accompanying drawings, forming a part of this specification.

10 My design relates to supporting-brackets for steam and other pipes; and it consists, first, of the novel form or configuration of such bracket, and, secondly, of the surface ornamentation thereof.

15 Referring to the drawings, Figure 1 is a front elevation thereof, and Fig. 2 a side view.

Referring first to the form or configuration, the bracket-plate is provided with rounded ends H H, with a thickened rim G all around 20 it, and curves upwardly to a central flat portion F, extending almost the length of the bracket-plate and terminating at each end in raised circular figures D D. At alternate distances on the said plate F are projecting 25 posts E and C. On each of the alternate posts C is an ornamental piece having a plate center a, with two arms A A curving outward and in the direction of the length of the bracket-plate.

30 Referring now to the surface ornamentation of the bracket, the said curved arms A A a are

shown in Fig. 1 to consist of a central rounded portion a, with the two curved ends A A again curving outward in width to about the center, and thence inwardly to a blunted point, with 35 a raised rim all around a groundwork of cross-lines, and on the groundwork a raised figure in the form of two leaves with a lily. The curved side B of the bracket-plate is ornamented with cross-lines d d for groundwork, and upon the same are raised figures b b in the form of two leaves with a lily in the center.

Having thus described my invention, what I claim as new is—

1. A design for the shape or configuration of a pipe-bracket, substantially as shown and described.
2. The design for the surface ornamentation of a bracket-plate and supporting-arms of a 50 pipe-bracket, substantially as shown and described.
3. The design for the shape or configuration and surface ornamentation of a pipe-bracket, substantially as shown and described.

In testimony whereof I have hereunto affixed my signature this 9th day of November, A. D. 1889.

JAMES H. ALEXANDER.
